LAWRENCE WESLEY HORNE, OF WOODRIDGE, AND WARREN NOBLE CRANE, OF RIDGEFIELD PARK, NEW JERSEY.

MAGNETIC CONTROL FOR TRAINS.

1,256,019.

Specification of Letters Patent. Patented Feb. 12, 1918.

Application filed October 28, 1914. Serial No. 868,923.

To all whom it may concern:

Be it known that we, LAWRENCE WESLEY HORNE and WARREN NOBLE CRANE, citizens of the United States, and residents of, respectively, said LAWRENCE W. HORNE of the town of Woodridge, county of Bergen, State of New Jersey, and WARREN N. CRANE, of the town of Ridgefield Park, county of Bergen, State of New Jersey, have invented certain new and useful Improvements in Magnetic Controls for Trains, of which the following is a specification.

This invention accomplishes the purposes described in many of our applications and particularly in the one filed March 4th, 1914, Serial #822,301, Patent No. 1,213,198, dated Jan. 23, 1917. In the development of that device we found certain changes could be made which although not absolutely necessary were exceedingly advantageous and therefore desirable. The changes are now incorporated in this application and may be summed up briefly as follows:

Increased efficiency, by shortening the air gaps in the magnetic fields. Overcoming the possibility of interruption because of excessive vibration. Reducing the required voltage and current flow of the source of electrical supply. Cheapening and simplifying the general construction and adapting the device for installation without radical changes in the standard equipment.

All of these improvements are necessary in that they independently and collectively operate to produce an apparatus much more flexible and more readily adaptable to any and all conditions.

The following is what we consider the best means of carrying out this invention.

40 The accompanying drawings form a part of this specification, in which:

Figure 1 shows partly in elevation and in diagram a portion of the track and the locomotive magnet and control.

45 Fig. 2 is an end elevation and partial section of certain of the elements shown in Fig. 1.

Fig. 3 shows in diagram a section of track.

50 Fig. 4 shows a modification in the construction of the movable core of the electromagnet 15.

Fig. 5 is a still further modification of this construction.

Similar reference numerals indicate like parts in all the figures where they appear. 55

This device is intended to control the speed or to check the motion of a train and to that end it employs a series of manganese or non-magnetic rail sections arranged in pairs as shown at 1-1', 2-2', and 3-3', in 60 Fig. 3, each pair of which are inserted predetermined distances apart and we arrange that the spacing between the sections of each pair shall be varied according to the requirements that shall be later described. 65 Except at the points wherein we have inserted diamagnetic sections the rails are ordinary steel running rails and in Fig. 3 the ordinary rails are indicated at 4, 4', 4'', 5, 5', 5'', 5''', and we also prefer that the 70 opposite rail of the usual pair shall be an ordinary steel rail. This rail is indicated at 6. All sections of ordinary steel rail are presumed to be subject to magnetic influence and well adapted to be attracted by or to 75 any magnet that may be brought into sufficiently close proximity thereto; therefore when a magnet is passed over these sections of ordinary rail a magnetic field will be established but when one of the diamagnetic 80 sections is reached the magnetic field will be shortened and confined within the magnet with the result that the magnet will not be influenced by the rail and it is because of the shortening of the field of the interruption of rail influence as it may be termed 85 that we obtain an operation of our device.

Under certain conditions it becomes quite desirable and even necessary that a magnetic field should be continued if not through the 90 manganese section at least sufficiently close thereto to induce the necessary mechanical action. In our device when the field of the magnet is shortened by passing over a diamagnetic section we maintain a magnetic 95 influence adjacent to the diamagnetic section by a plurality of coils as indicated at 7 and 8. Each coil we inclose in a casing 9 that will not only support it but that will protect it from injury. The casing should be 100 brass or other diamagnetic material and we prefer that each casing should be secured to the ties or to some other immovable support. The core of each of the magnets 7 and 8 is continued beyond each end of the coil as 105 indicated at 10 and 11, and is bent approxi-

mately at a right angle to terminate in an extending plate or T as indicated at 12 and 13, and we prefer that the arrangement of the coil casings should be such that the faces 5 of the cores should be about on a plane and quite close to the head of the adjacent rail.

The coils 7 and 8 and all of the coils arranged adjacent to diamagnetic sections will be included in the battery circuit or other 10 source of current supply that is provided for the signals which operate in the sections wherein our devices are disposed, but it may be advantageous to provide a separate source of current supply for these track 15 coils. The number of coils and the length and diameter of each as well as the length of each manganese section will be determined by the operative conditions as will be fully set forth in the description of the operation of our device.

Supported upon the locomotive and arranged within the line of the tread of the wheels thereof is a casing 14, which should also be constructed of diamagnetic material. 20 Within the casing we arrange a magnet coil 15 having a rotatable core 16, which may be supported by adjustable pins 17 and 18. Connected to the core and extending upward therefrom is an arm 19 supporting at 25 its upper end an insulated block 20, which has arranged in its upper face a contact strip 21. A spring 22 arranged between the upwardly projecting rod 19 and an adjacent side of the casing tends to rotate the magnet 30 core 16 so that its downwardly projecting ends will assume the position shown in the dotted line 23, but the inclusion of a steel rail in the field shortens the magnetic field by swinging the downwardly projecting end 35 of the core 16 into the position shown by the full lines 24 even against the pull of the spring 22. The contact strip 21 may be electrically connected to the upwardly extending rod 19 for a purpose that shall appear later.

Arranged within the casing and extending a certain distance along one of the longest sides is a pivoted member that we sometimes term an armature 25. This armature 50 which consists of a thin soft iron plate supported on a rod or pivot 26 is subject to the influence of the magnets 7 and 8 and when the magnets 7 and 8 are energized the free lower edge of the armature will be drawn outward. This will partially rotate the rod 26 which will in turn move a vertical bar 27 so as to close a plurality of contacts adjacent thereto.

These relatively operating track and 60 locomotive parts control a plurality of valves and a timing mechanism which in turn determine the time and speed at which the air brakes shall be applied by our device.

The air valves and timing mechanism 65 may be located in a cabinet indicated by the

dotted lines 30 in which may also be arranged the battery or source of current supply 31 and a protective or overload circuit breaker 32. A lead or pipe from the main reservoir is indicated at 33, and in this pipe 70 we arrange a reducing valve 37 and a magnetically operated valve 34. From the valve 34 a pipe 35 extends to a timing cylinder 36 and between the valve and timing cylinder we may arrange a speed washer or controller 75 38. A second valve 39 is arranged in the brake pipe or train line air circuit 40. This valve is also magnetically operated and exhausts directly into the atmosphere through a short lead or nipple 41. Arranged upon 80 each of the movable members of the valves 34 and 39 are disks 42, 43 respectively for a purpose that shall appear later.

The timing cylinder has a piston 44 urged upward by means of a spring 45 and connected to which is a rod 46 upon which we arrange contact disks 47 and 48.

Thus far we have described the mechanical construction of our device now however we shall detail its operation referring to the 90 mechanical parts by name or by reference character whenever it shall become necessary.

A locomotive carrying the necessary parts of our device approaches a diamagnetic 95 track section and if it is not intended that an operation of our device shall there occur the coils 7 and 8 will be energized by a closed track circuit the magnetic circuit through the rail will, however, be interrupted and the core 16 will turn to the position 23. This will interrupt the circuit through the contacts b—b bearing upon the block 21, but as the coils 7 and 8 are energized these coils will, just prior to the interruption of the magnetic path through the rails, draw the armature 25 outward and cause the vertical arm 27 to close the circuit through the contacts c—c. It will be noted that the contacts b—b and c—c are in multiple and therefore no interruption of the 100 normal condition will result from the discontinuance of the magnetic rail. When, however, it is intended to cause an operation by subsequent diamagnetic sections the coils 115 7 and 8 and all similar coils arranged adjacent to local non-magnetic sections may be deenergized with the result that when the core 16 swings to the position 23 a circuit controlled by the engine magnet will be interrupted and a second interruption by the diamagnetic section 1' within a specified 120 time will cause an operation of the reservoir or train line air valve.

We will now trace the circuits which 125 cause the desirable operations bearing in mind that our device operates on a closed circuit principle.

Under normal running condition a circuit from the battery 31 continues through the 130

circuit breaker 32 to the lead wires *d*, to *e*, to the coil 15, to F, and return to the battery. This insures that the coil 15 will be constantly energized. The control circuits 5 are from the lead wire *d*, to *g*, to the rod 19 through one of the contacts *b*, to *h*, to the valve 34 to *i*, to a contact *r*, adjacent to the timing cylinder and to another contact adjacent to the disk 42. The latter contact is 10 normally closed with a resistance *j*', which continues the circuit to a lead from the battery. From the second contact *h*, the circuit extends through the lead *h*, to the valve 39, and continuing through this valve passes 15 through the normally raised disk 43, through the resistance and wires *l*, *m*, to the battery.

When an interruption of the circuit through the valve 34 occurs because of the movement of the core 16, and the lack of energy which 20 would move the armature 25 the disk 42 is forced downward by the pressure of the air which opens the valve 34. The air passes into the timing cylinder 36 and the contacts *y*—*y*, *j*—*j* are opened. It will be noted that 25 the opening of the contacts does not occur immediately that the piston 44 starts in its downward movement as we have arranged for a certain amount of lost motion which will retard the opening of the contacts. The 30 piston 44 is controlled in its downward movement by the spring 45 which opposes the air pressure so that the piston moves deliberately and does not reach the end of its motion by a sudden impulse.

35 It will be understood that the movement of the core 16 and the interruption of the circuit is of short duration. The encountering of another section of ordinary steel rail will again cause the core 16 to return to the position 24 and the circuit through the contacts *b*—*b* to be re-established. Now if 40 the circuit be continued without interruption the piston 44 will continue downward until the disk 47 reaches the contacts *r*—*r*, which will in turn energize and close the 45 valve 34 shutting off the air that has forced the piston downward. The piston will then commence to return but the interruption or the breaking of the circuit across the contacts *r*—*r* will not re-open the valve 34 as 50 the circuit through this valve will be continued complete through its own disk and through the contacts *b*—*b* or *e*—*c*. In connection with this operation we may observe 55 that the extent of lost motion in the disk 47 will be sufficiently great to forbid a movement of the disk until the train magnet has reached another ordinary steel rail section.

60 Consider however that while the piston 44 is moving downward a second interruption of the circuit across the contact *b*—*b* shall occur by reason of the approach of a diamagnetic rail section and that for a second time no current is passing through the 65 coils 7 and 8. The second interruption will

deenergize the valve 39 allowing it to open and setting the train brakes. It will be fully appreciated therefore that we may obtain not only a complete stopping of the train but a speed control as it is very evident that the piston 44 may be caused to operate as rapidly as desired, and that any given time may be allowed between diamagnetic sections without effecting an operation of the brakes but in every instance 70 the time will be controlled by the distance, between the diamagnetic sections and the speed or rapidity of the operation of the piston 44. To adjust this speed we have provided the fitting 38 wherein is arranged 80 a speed washer which consists of a disk, having a central perforation of any predetermined diameter. The operation of devices of this kind is fully understood.

It is will be appreciated that we have not, 85 in this application intended to describe every advantage to be gained from the operation of our device nor every modification that may be made in the construction. We have only detailed the device to an extent sufficient to cause it to be fully understood, and it is obvious that modification may be made within the scope of the appended claims without departing from the principle or sacrificing the advantages of this invention. 95

One of the most important reasons for the peculiar construction of the train magnet is the desire to overcome the possibility of an interruption of the operation because of or by vibration we have 100 shown a construction which has been fully described in connection with Figs. 1 and 2 that we believe will operate successfully, but this construction provides for the maintaining of the downwardly depending ends 105 of the rotatable core 16 away from the center line of the running rail. This will cause a slight distortion of the magnetic lines from the rail to the magnet core and although this is not objectionable it does require a greater current flow than would be necessary were the core arranged in the center line of the rail. 110

In Fig. 4, we show a train magnet coil having a movable core in two parts 55 and 115 56 connected by a joint 57 both of the parts 55, 56 should be of iron and the joint 57 is so constructed that a close engagement of the parts is obtained and so that no distortion of magnetic lines will result from the 120 introduction of the joint. Secured to the bottom of the casing and projecting inward therefrom is a lug 58, provided with a slot 60 in which we have arranged a free moving pin 61. The pin engages the lower end of 125 the core section 56. A spring 62 tends to break the joint between the parts 55, and 56 at the joint 57 and the magnetic pull occasioned by the presence of an ordinary steel rail tends to straighten the toggle on the line 130

63. Objectionable vibration occurs only when the core extensions of the coil are in a vertical position, the position assumed over an ordinary steel rail, as the toggle will then 5 be in a straight vertical line vibration will not tend to operate the parts and interrupt the circuit.

In Fig. 5 we show a construction wherein the movable core or the projections therefrom may be disposed at or over any convenient point. The core in this instance is provided with off-set depending ends as indicated at 50 and we provide a counterweight 51 of sufficient weight to exactly balance the 15 projection 50 as these two parts are suspended from a common center and as the gravity attraction is equal in both instances vibration will not effect the position nor will it tend to rotate the projection 50 and the 20 weight upon its center.

In this construction the spring 52 which lifts the projection 50 upon the interruption of the magnetic field is secured directly to the projecting arm and to a block 53 which 25 may be attached to an adjacent end of the coil. The upwardly extending contact arm is of a construction and operation fully described in connection with the arm or rod 19.

Having carefully and fully described our 30 invention what we claim and desire to secure by Letters Patent is:—

1. A device for controlling the speed of trains comprising a controlling mechanism carried by a locomotive, an ordinary track 35 having a plurality of diamagnetic sections, a plurality of magnetic coils arranged parallel and adjacent certain diamagnetic sections and adapted to coöperate with said diamagnetic sections to alternately operate and retain inoperative said controlling mechanism as and for the purpose set forth.

2. A device of the character described comprising an ordinary rail, diamagnetic sections arranged at predetermined points 45 therein, a plurality of independent electromagnetic units adjacent to alternate diamagnetic sections and a magnetically influenced device carried by a locomotive and adapted to be operated by said diamagnetic sections

and to be sustained in an inoperative position by said electromagnets as and for the purpose set forth. 50

3. A device of the character described comprising a plurality of electromagnetically operated devices, and means for maintaining or interrupting the circuits therethrough, said means comprising a plurality of contacts, a magnet for operating them, said magnet being supported adjacent to the rails and a plurality of contacts in parallel 60 with said first mentioned contacts and operated by a second magnet remote from said first mentioned magnet as and for the purpose set forth.

4. A device of the character described 65 having an air valve, a timing cylinder, connected therewith and a second valve controlled by said timing cylinder, means for operating said first valve to admit air to operate said timing cylinder, a magnet, a sup- 70 porting member therefor arranged adjacent to a rail for maintaining the said air valves in a closed condition during a portion of the operation, and a device in movable relation to said magnet supporting member for main- 75 taining said air valves closed during another portion of the operation all arranged for joint operation for the purpose set forth.

5. A device of the character described comprising magnetically operated valves one 80 of which controls the operation of the other and means for operating said valves, said means including an electromagnet having a partially rotatable core, and a circuit breaking device for one of said valves operated by 85 said core in combination with a magnetic member for retaining said core and a diamagnetic member in the path of said core for releasing said core as and for the purpose set forth. 90
